UNITED STATES PATENT OFFICE.

LEO F. LECHTEMERG, OF QUINCY, ILLINOIS, ASSIGNOR, BY MESNE ASSIGNMENTS, TO
ROWSEY GASOLINE PROCESS COMPANY, OF HUMBOLDT, KANSAS, A CORPORATION
OF KANSAS.

TUBE-SCRAPING APPARATUS.

1,343,215.

Specification of Letters Patent. Patented June 15, 1920.

Application filed May 7, 1917. Serial No. 166,833.

To all whom it may concern:

Be it known that I, LEO F. LECHTEMERG, a citizen of the United States of America, a resident of Quincy, in the county of Adams, State of Illinois, have invented certain new and useful Improvements in Tube-Scraping Apparatus, of which the following is a full, clear, and exact description, reference being had to the accompanying drawings, forming a part of this specification.

My invention relates to a scraping apparatus adapted to remove accumulations of carbon and coke from the tubes of apparatus used in the distillation of hydrocarbon oils. One of the objects of the invention is to provide efficient means for cleaning the inner faces of the tubes. More specifically stated, one of the objects is to produce an improved scraper feeding mechanism, and another object is to provide an efficient scraper, adapted to cooperate with said feeding mechanism.

With the foregoing and other objects in view the invention comprises the novel construction, combination and arrangements of parts hereinafter more specifically described and illustrated in the accompanying drawings wherein is shown the preferred embodiment of the invention; however, it is to be understood that the invention comprehends changes, variations and modifications which come within the scope of the claims hereunto appended.

Figure I is a vertical cross section.

Fig. II is an enlarged cross section on line II-II, Fig. I.

Fig. III, is an enlarged cross section on line III-III, Fig. II.

In the drawings I have shown portions of an apparatus for use in the distillation of hydrocarbon oils, such portions comprising a header A and tubes B in communication with said header, these parts being those of a still in which hydrocarbon oils are treated to crack them. In the use of such parts in oil cracking operations there is a constant tendency toward the collection of coke and carbon upon the inner surfaces of the tubes B, and if the accumulations are not removed from time to time the tubes become partially or wholly clogged and there is serious interference with the carrying out of the intended oil cracking opera-

tions. The apparatus to which my present invention pertains is intended to be so associated with the members of an oil still, such as those described, as to be constantly ready for service, and operable when required, for the removal of accumulations of carbon and coke from the interior surfaces of the tubes of the still.

Proceeding now to the description of my scraping apparatus. C designates circular scrapers movable to and fro longitudinally within the tubes B, each of these scrapers comprising a perforate central portion surrounded by a rim 1 and having a central hub 2 (see Fig. II). The rim of each scraper is concaved transversely at its periphery, thereby providing at each edge of the rim a scraping edge which is adapted to move adjacent to the inner wall of a tube in which the scraper is situated to separate accumulations of carbon or coke from said wall. One of the rim edges just mentioned is effective when the scraper is moved in one direction, and the other edge is effective when the scraper is moved in the opposite direction.

The scrapers C are made of perforate form to permit movement of the contents of the still through the tubes B, notwithstanding the presence of the scrapers therein, and it is obvious that accumulations of carbon and coke in the openings in the scrapers will occur in the same manner as they occur upon the interior walls of the tubes B. I therefore provide for the removal of accumulations from the openings in the scrapers by mounting at one end of each tube B a scraper cleaner D, comprising a head 3 and a plurality of separated punches 4, the number of which is preferably equal to the number of openings in the scraper movable toward and away from a particular cleaner D. It will be readily understood that when a scraper C is moved to a cleaner D, the punches of the latter may be readily caused to pass through the openings in the scraper to dislodge accumulations therefrom.

The scrapers C are intended to move longitudinally of the tubes in which they are operable without partaking of rotation during their movement, and they may be held from rotation by any suitable means, such, for example, as a guide 5 secured to the tube and extending longitudinally thereof, each

scraper containing a notch into which the guide extends.

While I have shown a plurality of tubes B and a corresponding number of my scrapers and cleaning devices, I will in the following description of the means for operating the scrapers allude, in the main, to only one of them, inasmuch as a description of the means for operating one of the scrapers may be considered to apply with reference to the operation of the others.

6 designates a feed screw extending longitudinally of a tube B and to which the screw threaded hub of the scraper C in said tube 15 is fitted. Obviously, inasmuch as the scraper is held from rotation in the tube, as previously explained, it will be caused to travel longitudinally in the tube when the feed screw is turned in one direction, and it 20 will travel longitudinally in the tube in a reverse direction when the feed screw is rotated reversely, and in each direction of the movement of the scraper the foremost edge at the periphery of the scraper will act to sever accumulations of carbon or coke from 25 the inner wall of the tube.

The scraper operating mechanism of my tube scraping apparatus includes means whereby the direction of rotation of the feed 30 screw is automatically reversed as the scraper reaches the limit of its travel in either direction, and this means will be hereinafter described. The feed screw 6 is provided at one end, which extends into the header A, with a bevel pinion 7 arranged in mesh with a bevel gear wheel 8 fixed to a feed screw operating shaft 9 extending longitudinally in the header A.

In the operation of my apparatus the tube scrapers C are moved longitudinally in the tubes B, first toward one end of each tube and then toward the opposite end of each tube, these movements of the scrapers being occasioned by the rotation of the feed screws 6, first in one direction and then in the opposite direction. Each time that a scraper reaches the end of a tube at which the cleaner D is located the punches of the cleaner pass through the openings in the scraper and dislodge any accumulation that 50 may have taken place therein. All of the feed screws 6 are operated by the feed screw operating shaft 9, which is rotated first in one direction and then in the opposite direction. 55

I claim:—

1. In a tube scraping device, a perforated scraper adapted to engage the inner face of a tube, and a scraper cleaner provided with projecting portions adapted to extend through the openings in the scraper to remove accumulations of material therefrom. 60

2. In a tube scraping device, a perforated scraper adapted to engage the inner face of a tube, a scraper cleaner provided with projecting portions adapted to extend through the openings in the scraper to remove accumulations of material therefrom, and means for reciprocating said scraper to scrape material from the inner face of the 70 tube, said scraper cleaner being located at one end of the path of movement of said scraper. 65

In testimony that I claim the foregoing I hereunto affix my signature.

LEO F. LECHTERBERG.
